HERBERT M. KNIGHT, OF MONTCLAIR, NEW JERSEY

STRUCTURAL ELEMENT

Application filed June 24, 1927. Serial No. 201,075.

This invention relates to improvements in means for forming key-ways in pre-cast slabs and has particular reference to a metallic means for forming said key-ways.

5 One of the objects of the invention is to provide a thin metallic sheet so pressed, as that, when inserted in the mold or form into which the plastic material of the slab is to be poured, a key-way is automatically created by 10 the presence of such metallic sheet. Another object of the invention is to provide a metallic key-way forming means, which at the same time acts as a surrounding and protecting means to the slab adjacent to said key-way. A 15 third object of the invention is to provide such a key-way forming means, which by suitable returns is tied into and immovably cast into the structure of the slab. A fourth object of the invention is to provide a key-way forming means which is united with a reinforcing means within the slab, the said forming means and the said reinforcing means acting together to strengthen the slab at and adjacent to the groove or key-way formed by the said 20 means. Other objects of the invention will appear from the following description and from the accompanying drawings.

The accompanying drawings, Figures 1 to 6 inclusive, illustrate the usual and preferred embodiment of the invention, but are not to be considered as inclusive of any and all forms in which the invention may be embodied, nor as exclusive of forms other than those indicated.

25 Referring to said accompanying drawings in which like numerals of reference indicate similar parts throughout the several views:—

Figure 1 is an isometric view of a key-way forming metallic member, inserted in the 30 mold or form for the slab, and before the pouring of said slab;

Figure 2 is a cross-section of a slab at the key-way, after pouring, and while still within the slab forming mold, showing the metallic key-way forming member and the method 35 of attachment to a reinforcing means;

Figure 3 is an elevation of an edge of the key-way forming member and indicates attachment thereof to a reinforcing member;

50 Figure 4 is a cross-section of a slab, at a

key-way, indicating a plain key-way forming member;

Figure 5 is a cross-section of a slab, at a key-way, indicating a corrugated key-way forming member; and

55

Figure 6 is a cross-section of a re-entrant groove or key-way bounded by rectilinear lines.

In the specific embodiment of the invention illustrated in said drawing, the reference 60 numeral 1 indicates a pre-cast slab within a mold or form 2. A metallic key-mold 3 serves to form a key-way 4. Lug extensions 5 are embedded in the mass of the slab, said lug extensions preferably having perforations 6 65 through which the concrete may tie together. Reinforcing members 7 are shown in the body of the slab and may be engaged by the curled ends 8 of said lug extensions if desired. Tack holes 9 provide for initially retaining the key-mold in position in the form. Check-blocks 70 10 are inserted between said form and said key-mold to prevent mass material entering therein.

In forming a pre-cast slab in which a 75 groove or key-way is an integral and important part, the creation of the void which constitutes the key-way is a difficult operation. A core, of wood, or other material, is employed, which said core has to be subsequently 80 removed in order that the designed void representing the groove or key-way may exist. The removal of this core is difficult and expensive, and in cases where the groove is long it sometimes becomes impossible to make a 85 perfect removal of the said core.

This invention overcomes all of the objections inhering in the use of solid cores, by substituting a thin metallic sheet which is bent into the shape which it is desired that the 90 groove shall have, and which is inserted into said mold in advance of the pouring of the slab material. When the material hardens it holds the key-mold firmly in the desired position and of the designed form.

Again, in slabs having grooves or key-ways therein, especially where the groove is of a re-entrant type, the presence of such groove becomes an element of weakness in the slab. The reinforcing of this weaker element, and 100

the uniting of the reinforcing elements of the slab with this weaker portion, where the key-way has been formed by the use of a solid core, is difficult and often impossible. The 5 removal of the solid core, when attempted in advance of the complete curing of the slab, is often attended with cracking or fracturing of the slab at or near the key-way.

This invention overcomes all of these hazards and difficulties by providing a key-way forming means which strengthens the slab at this, its otherwise, weakest portion, and at the same time provides an adequate means for uniting the key-way portion of the slab to 15 the reinforcing elements of the slab, so that the entire slab acts as one to resist stress and disruption.

By creating lugs on the metallic plate which lugs are bent inwardly into the mass 20 of the slab, the plate becomes held firmly within the slab mass. The ends of these lugs are coiled around the reinforcing members, to which they are, or may be, welded. By such welding together of the lugs and reinforcing frame the whole structure of key-forming mold and reinforcing members becomes a unit which may be inserted as one 25 into the slab form in advance of the pouring of the slab. Such welding of these two elements still further augments the strength of the slab at or near the key-way portion.

By the use of a metallic key-way form, difficult or involved key-ways, such as corrugated, 30 may be easily made, such as shown in Fig. 5.

35 The invention is susceptible to various shapes or configuration of key-ways as well as various constructions for tying the metal form permanently into the slab or structural element, and while I have shown several embodiments of the invention, it is to be understood that I do not restrict myself to any of these forms, as various modifications and changes may be made in manufacture and use, and I do not limit myself except as set forth 40 in the following claims when construed in the light of the prior art.

Having thus described my invention, I claim:

1. In a pre-cast slab the combination of 50 a plate as a key-way forming means, lugs on said means, a reinforcing element, and means engaging said lugs and said element.

2. In a pre-cast slab the combination of a plate as a key-way forming means, lugs on 55 said means, a reinforcing element and means engaging said lugs and said element, and said lugs having perforations for entry of the material therein during casting of the slab binding the material on opposite sides of the 60 lugs.

3. In a pre-cast slab, the combination of a plate forming a re-entrant groove, said plate having end extensions directed inwardly and embedded in the material forming the slab, said extensions having perforations for

entry of the material therein during casting of the slab binding the material on opposite sides of the extensions.

4. In a pre-cast slab having an end face and side faces at an angle to and intercepting 70 said end face, the combination of a plate also providing an end face extending entirely across the end face of said slab and having side faces extending partly over the side faces of the slab said end face of the plate 75 having a re-entrant groove enabling the slab to be keyed through the end face to another similar slab.

5. In a pre-cast slab having an end face and side faces at an angle to and intercepting 80 said end face, the combination of a plate also providing an end face extending entirely across the end face of said slab and having side faces extending partly over the side faces 85 of the slab said end face of the plate having a re-entrant groove therein midway between the said side faces providing a symmetrical structure.
